UNITED STATES PATENT OFFICE.

FRED D. STELLJES, OF NEWARK, NEW JERSEY, ASSIGNOR TO THE T. & L. CO., INC., OF NEWARK, NEW JERSEY, A CORPORATION OF NEW JERSEY.

BAG LOCK.

Application filed February 7, 1927. Serial No. 166,403.

This invention relates to improvements in locks of the type used in connection with hand bags in which the frame members may be yoked by pressing them into a closed position and thus held until released by manual operation.

In such locks it has hitherto been customary to permit the release plunger to be depressed by the action of an entering catch, thereafter rising, by reason of impelling springs, to engage and retain the catch, means being provided, movable by a key, to hold the plunger in a raised position, thus actually locking the frame members together and preventing their separation until unlocked.

It is one of the objects of the present invention to provide means for retaining the release plunger in a depressed position when the bag is in an open condition, allowing it to rise only after the catches have been fully entered in the lock casing and are in position to become engaged therein, thus avoiding excessive and unnecessary movement by which wear is incurred.

A further feature is in the simplification of parts employed and in the production of a lock of unusually attractive appearance due to the absence of extending elements.

These and analogous objects are attained by the novel design, construction and combination of simple parts hereinafter described and illustrated in the annexed drawing in which:—

Figure 1 is a perspective view of a portion of the sides of a conventional type of bag provided with a lock made in accordance with the invention.

Figure 2 is a longitudinal sectional view of the lock taken in a plane parallel with and below the cover plate.

Figure 3 is an enlarged transverse sectional view taken in a plane passing through the lock and bag frame members.

Figure 4 is an inside plan view of the lock casing back plate, showing the plunger retaining spring thereon.

Figure 5 is a fragmentary top plan view, similar to Figure 2 but showing a modification of construction.

In the drawing the bag covering is designated by the numeral 10, the same connecting with individual frame covers 11 and 12 disposed over the respective frame elements 13 and 14, both of which are of right angular cross section, the former being considerably less in its dimensions to permit being closed within the other.

Rigidly secured on the inner side of the frame element 13 are a pair of spaced right angled catches 15 containing openings 16.

Fixed on the frame member 14 is an escutcheon 17, through the central opening of which slightly projects a plunger 18 containing a revoluble key guide 19, the same having a slot registrable with a corresponding slot in the plunger top and through which a key may be entered to actuate a shift plate 20 within the lock casing the plate being provided with projections which prevent the plunger from being pressed inwardly when the plate is in one position and permit depression of the plunger when in another position.

The plunger 18 is surrounded by a guide 21 riveted to the top wall of a lock casing designated generally by the numeral 22, the same having flanged ends 23 to which is riveted the corresponding ends of a back plate 24 forming the rear wall of the casing, these ends being rigidly secured to the vertical element of the frame member 14.

Formed through the front wall of the casing are openings 25 through which the catches 15 enter to engage the cam faces of keeper detents 26, slideable on and guided by rods 27 and pressed normally upward by encircling compression springs 28, the rods being riveted in openings in the bottom wall of the casing.

These detents are slideable against the inner surface of the front wall of the casing and are adapted to engage in the catch openings 16 to retain the bag sides in closed position; the detents normally abut the top or cover plate of the casing and are integrally connected by a plate 29 extending therebetween in which is revolvably mounted the reduced inner end of the key guide 19.

The sides 30 of the plunger 18 are ex-

tended downwardly to pass through openings in the plate 29 and thereafter bent tightly over to be rigidly engaged, thus binding the plunger and detents as a unit. Thus it will be seen that when the plunger 18 is depressed the detents 26 will be forced down into position to release the catch loops 15 and permit the bag to be opened, and it will be obvious that the plunger is normally raised by the springs 28.

A rivet 31 passes through the upper central portion of the back plate 24 to secure against its inner side a bent flat leaf spring 32, the same being of such width as to fill the space between the plate 29 and top member of the casing 22, the end portions of the spring moving forward to engage in the space at such time as the plunger is fully depressed to hold the same in its extreme lowered position until the catches 15 have been fully entered to press the ends of the spring outwardly causing release of the plunger and detents and consequently raising these elements to their normal positions.

When so released the compression springs 28 raise the plunger and keeper detents into engaging position, thus locking the frame sides together, such locking being made positive by key shifting the plate 20 into position to intercept depression of the plunger 18.

It is to be noted that the walls of the casing are rigidly secured by integral lugs bent over at their ends as shown forming a firm and substantial structure, and that one or more of the locks may be used as desired each being independent of another.

In the modification shown in Figure 5 a simplified construction is disclosed, avoiding the use of separate spring elements 32 and the rivet 31 entirely.

A thinner back-plate 34 of spring metal is substituted for the previously described plate 24 and extends from end to end of the lock casing to which it is secured by rivets.

The upper portion of the plate 34 is sheared to present two opposed inreaching arms 35 having incurved terminals against which the catches 15 make contact when the bag is closed, displacing the same in the same manner and for the same purpose that the elements 32 are displaced as herein before described.

Although I have described my improvements with considerable detail and with respect to certain particular forms of my invention, I do not desire to be limited to such details since many changes and modifications may well be made without departing from the spirit and scope of my invention in its broadest aspect.

Having thus described my invention, what I claim as new and desire to secure by Letters Patent, is:—

1. A bag lock comprising, in combination with a casing on one frame member having a

spring actuated plunger, keeper detents associated therewith and catches on the other frame member engageable with said detents, means wholly within said casing to retain said plunger in a depressed position until said catches have become engaged by said detents. 70

2. A bag lock comprising, in combination with a casing having a slideable plunger on one frame member and a catch on the other frame member to enter said casing, a spring 75 actuated keeper to engage said catch, said keeper being a unit with said plunger, and a spring detent on the inner rear wall of said casing to intercept said plunger when in a receded position until released by entry of 80 said catch.

3. A bag lock comprising, in combination with a casing having a slideable plunger on one frame member and a catch on the other frame member to enter said casing, a pair of 85 rods in said casing, detent catches slideable on said rods, means on said rods to normally project said detents into engaging position, means slideable longitudinally in said casing to prevent said detents from depression when 90 said lock is closed, and means in said casing to prevent operative projection of said detents when said lock is open.

4. A bag lock comprising, in combination with a casing having a slideable plunger on one frame member and a catch on the other frame member to enter said casing, a pair of rods in said casing, a plate slideable on said rods, said plunger being connected with said plate, cam faced detents formed on said plate, a key 95 actuatable shift plate movable in said casing to control the movement of the first named plate, and a flat resilient spring in said casing engageable intermediate the first named plate and the top wall of said casing. 100

5. A bag lock comprising, in combination with a casing having a slideable plunger on one frame member and catches on the other frame member to enter said casing, a pair of 110 detents slideable in said casing, a plate connecting said detents, connections between said plate and said plunger, and a flat spring in said casing adapted to engage said plate upon depression of the same until re-entrance of the frame catch. 115

6. A bag lock comprising the combination with a pair of bag frame members, of looped catches on one frame member, a casing on the other frame member, a depressible plunger in said casing, a plate actuated by said 120 plunger, said plate being normally spring pressed towards the top of said casing, detents on said plate engageable with said catches, and means on the rear wall of said casing to retain said plunger, plate and detents in a depressed position, said means being released upon entering the catches fully within the casing. 125

7. A bag lock comprising the combination with a pair of bag frame members, of a pair 130

of looped catches on one frame, a casing on the other frame, a spring pressed plunger extending above the surface of the top wall of said casing, a detent carrying plate fixed on the inner end of said plunger, said detents to engage in the looped catches, and a pair of spring arms on the rear wall of said casing to

retain said plate, detents and plunger when the plunger has been depressed, said arms being retracted to release the plate upon contact by the entered catches. 10

This specification signed and witnessed this third day of February, 1927.

FRED D. STELLJES.
